Primary Examiner — Barbara Fox*Assistant Examiner* — Lorna M Georges(74) *Attorney, Agent, or Firm* — Sheridan Ross P.C.(57) **CLAIM**

The ornamental design for a power semiconductor module as shown and described.

DESCRIPTION

FIG. 1 is a perspective view of a power semiconductor module;

FIG. 2 is a front elevation view of the power semiconductor module;

FIG. 3 is a rear elevation view of the power semiconductor module;

FIG. 4 is a left side elevation view of the power semiconductor module;

FIG. 5 is a right side elevation view of the power semiconductor module;

FIG. 6 is a top plan view of the power semiconductor module; and,

FIG. 7 is a bottom plan view of the power semiconductor module.
